UNITED STATES PATENT OFFICE.

RAYMOND P. CLARK, OF ROCHESTER, NEW YORK.

COVER FOR FRUIT-BASKETS.

1,110,042.

Specification of Letters Patent. Patented Sept. 8, 1914.

Application filed January 20, 1913. Serial No. 743,089.

To all whom it may concern:

Be it known that I, RAYMOND P. CLARK, a citizen of the United States, residing at Rochester, in the county of Monroe and 5 State of New York, have invented certain new and useful Improvements in Covers for Fruit-Baskets, of which the following is a specification.

The object of this invention is to provide 10 a strong, durable cover for an ordinary fruit basket, which cover will protect the fruit against bruising or mutilation and at the same time leave it exposed for inspection.

Another object of this invention is to provide 15 vide a packing strip or ring between the cover and the peach basket.

Another object of the invention is to provide 20 a padded bottom for the bottom of the fruit basket.

These and other objects of my invention will be fully illustrated in the drawings, described in the specification and pointed out in the claims at the end thereof.

In the accompanying drawings Figure 1 25 is a perspective view of a fruit basket with my improved cover in place thereon and the packing ring interposed between the cover and the basket. Fig. 2 is a perspective view 30 of the improved cover with the packing ring thereunder. Fig. 3 is a perspective view with the central opening of the cover closed by a cover piece. Fig. 4 is a vertical section along the line 4[—]4^x of Fig. 1. Fig. 5 is a 35 detail view of one of the segments used in the construction of the cover.

In the accompanying drawings like reference numerals refer to like parts.

In the drawings reference numeral 1 indicates a peach basket of the usual well known 40 type. 2 indicates a cover therefor. This cover is made up of four sections 3, one of which is illustrated in detail in Fig. 5. The cover is made up of an upper layer 2^a and a lower layer 2^b, each of which layers is 45 composed of two of the sections 3 illustrated in Fig. 5. These sections 3 may be made with any desired material but preferably of wood. The cover is assembled by first bringing two of the sections together 50 so as to form a complete circle forming the lower layer of the cover. A round or circular piece of tarlatan is then laid upon this layer. Then two other sections 3 are laid

upon the lower layer to form the upper layer for the cover, with the joints between 55 the sections of the upper layer breaking joints with the joints of the lower layer. The parts thus assembled are fastened together in any suitable manner, as by nailing, by which the tarlatan is held in place 60 clamped upon the layers. Additional means may be used for holding the tarlatan in place, as by gluing. It will be noticed, as is illustrated in Fig. 4, that the inner lower edge of the layer 2^b is beveled so as to avoid 65 the possibility of having the fruit cut on the inner edge of this layer. On top of the cover so formed are placed the cross strips 4 and 5. The strip 4 is nailed securely in place at both ends. The strip 5 is nailed 70 securely at one end and the other end is left temporarily free or open. The strips are placed so as to cover the joints between the sections of the upper and lower layers, so that the nails which are used to fasten the 75 cross strips in place each pass through three thicknesses of wood and the strips themselves serve to hold together the sections of the layers.

As shown in Figs. 2 and 3, the left hand 80 end of the cross strip 5 is left unsealed or open. This permits the cover piece 9 to be inserted in the cover so as to be placed below the cross strips 4 and 5 and above the tarlatan of the cover. After the cover piece 85 has been thus inserted the free end of the cross strip 5 may be sealed in place by nailing, or in any other desired manner. If preferred, the free end of the cross strip 5 may be left unsealed until the cover is 90 placed in position on the basket, when it may be fastened down by means of one of the staples 8. This makes it possible for the packer to close the basket more easily, and also makes it easy for the prospective 95 purchaser to examine the fruit by simply removing the staple from the free end of the cross strip 5 and then draw out the cover piece 9.

Underneath the cover may be placed the 100 packing strip or ring 6 which is made preferably of corrugated paper and is annular in shape or ring shaped, and is of substantially the same width as the sections 3 of the cover. This packing ring is interposed 105 between the top of the basket and the cover.

The object of this packing ring is to introduce a cushion between the wooden part of the cover and the fruit underneath, so as to the better protect the fruit against being bruised, although it will be understood that my improved cover may be used with the basket without this packing strip. The packing strip also raises the cover slightly above the basket, permitting the basket to be filled in the center so that it can be full when the cover is removed.

At the bottom of Fig. 4 I have shown a cushion bottom 7 placed at the bottom of the basket for the purpose of affording a cushion on which the fruit may rest to prevent unnecessary bruising of the fruit that makes contact with the bottom of the basket. The cushion bottom and the solid bottom are each provided with an opening for ventilation.

The basket equipped with my various improvements may now be described as follows: First, the cushion bottom is placed in the bottom of the basket. The fruit may then be placed in the basket, the packing ring 6 may then be placed on top of the basket or omitted, as may be desired. The cover 2 may then be placed upon the basket and fastened in place by the staples 8 by which the cover and the basket are securely held together. If desired, before the free end of the cross strip 5 is fastened down by the staple, the cover piece 9 may be inserted and then sealed in by the staple that is applied to the free end of the packing strip. If desired the free end of the cross strip 5 may be nailed down in place with or without the cover piece 9 in place in the cover. This of course can be done before the cover is applied to the basket.

I claim:

1. In a cover for a fruit basket, the combination of a frame composed of two annular layers of greater width than thickness, the width of said layers being sufficient to extend the layers for a substantial distance into the radius of the basket whereby a support is formed for the fruit when the basket is inverted, one of said layers breaking joint with the other layer, and a layer of transparent fabric occupying the open center of said annular layers and having its edge confined therebetween, all of the said parts being securely fastened together.

2. In a cover for a fruit basket, the combination of a frame composed of two annular layers of greater width than thickness, the width of said layers being sufficient to extend the layers for a substantial distance into the radius of the basket whereby a support is formed for the fruit when the basket is inverted, each of said layers comprising two sections, one of said layers breaking joint with the other layer and each of said layers having its joints substantially

at right angles to the other layer, and a sheet of transparent material occupying the open center of said layers and having its edge confined therebetween, all of said parts being securely fastened together.

3. In a cover for a fruit basket, the combination of a frame composed of two annular layers of greater width than thickness, the width of said layers being sufficient to extend the layers for a substantial distance into the radius of the basket whereby a support is formed for the fruit when the basket is inverted, a sheet of foraminous material occupying the open center of said layers and having its edge confined between the layers, and strips fastened to one of said layers and extending thereacross and across each other, all of said parts being securely fastened together.

4. The combination in a cover for a fruit basket of an annular frame, a circular piece of tarlatan fastened therein, cross strips fastened to said frame and extending across each other, an opening between the end of one of said strips and the frame, a cover piece for filling the annular opening in said frame capable of movement into and out of place through the opening between said strip and said frame.

5. In a cover for a fruit basket, the combination of a frame composed of two annular layers of greater width than thickness, the width of said layers being sufficient to extend the layers for a substantial distance into the radius of the basket whereby a support is formed for the fruit when the basket is inverted, and a layer of transparent cloth occupying the open center of said layers and having its edge confined between the layers, all of said parts being securely fastened together.

6. A cover for a fruit basket comprising two annular layers of greater width than thickness, the width of said layers being sufficient to extend the layers for a substantial distance into the radius of the basket whereby a support is formed for the fruit when the basket is inverted, a layer of transparent cloth occupying the open center of said annular layers and having its edge confined between said layers, all of said parts being securely fastened together, and strips fastened to one of said annular layers and extending thereacross and across each other.

7. A fruit basket cover having a frame with a central opening, the diameter of said opening being sufficiently less than the inner diameter of the basket to extend the frame for a substantial distance into the radius of the basket whereby a support is formed for the fruit when the basket is inverted, and a piece of transparent fabric occupying the open center of said frame having its edges fixed to said frame.

8. The combination in a cover for a fruit

basket, of an annular frame, a piece of tar-
latan fastened therein, cross strips fastened
to said frame and extending across each
other, one of said strips being unattached to
5 the frame at one end to provide an opening
between the strips and the frame, and a
cover piece adapted to fill the opening in
said frame and capable of movement into

and out of place through the opening be-
tween said unattached strip and the frame. 10

In testimony whereof I affix my signature
in presence of two witnesses.
